VACUUM TUBE

Philip E. Edelman, New York, N. Y., assignor, by
mesne assignments, to Robert T. Mack, trustee,
Chicago, Ill.

Application August 25, 1923. Serial No. 659,263

18 Claims. (Cl. 250—27.5)

An object of the present invention is to provide an economical simplified apparatus which is sensitive and stable in operation, faithful in reproduction, and satisfactory in volume.

5 A further object is to provide vacuum tube apparatus in which the heating element or filament may be easily renewed, thus greatly increasing the useful life of such tubes.

These objects and others will presently appear 10 as reference is made to the accompanying drawing in which Figure 1 is a schematic diagram, by way of example, of a suitable radio vacuum tube, embodying my invention.

My invention relates more particularly to the 15 improved vacuum tube construction herein set forth whereby a good tight seal is obtained in the tube per se, permitting the heater for the cathode to be renewed without breaking said seal. The vacuum tube improvement set forth 20 can be used in any standard type of radio receiver or circuit, operated from any suitable source of current. It comprises a glass or quartz container 11 having an indented portion 14 within which the heating element 15 may be inserted or withdrawn 25 without disturbing the vacuum in tube 11. Tube 11 has seals 10 supporting respectively the plate or anode 13, the grid or control electrode 12, and the wire 9 which connects with the electron emitting surface 8. The electron emitting surface 8

30 may be constructed by depositing a platinized film coating 22 on the indented portion 14 of tube 11. On this platinized film 22 to which wire 9 is electrically connected, are placed coatings of electron emitting mixed metallic oxides, such as 35 calcium, bismuth, and strontium oxides. Any other suitable electron emitting surface may be connected to the wire 9. The heating element 15 transfers heat to the electron emitting surface 8 by conduction and radiation through the thin 40 portion 14 of tube 11. This heater 15 can be constructed in any suitable manner, preferably from fine nichrome or other heating wire material which does not readily oxidize. The heater 15 is supported by wires 16 in a removable insulating 45 plug 17 which fits on tube 11. When the heater or filament 15 burns out the plug 17 can be removed without disturbing the tube 11 or its connections and without breaking its vacuum, so that a plug 17 with a refilled heater 15 can be 50 inserted back in place, as shown. This affords a tube having good operating characteristics with economy in operation.

It may be remarked that the heater element 55 15 preferably comprises a re-entrant looped wire 15, as shown in the figure, which is normally sub-

stantially spaced from and not disposed against insulator 14. The electromagnetic field of force normally set up by passage of electric current through one leg of U-shaped heater filament 15 thereby tends to oppose that set up by the return passage of the same current through the other leg thereof and to minimize undesired electromagnetic force action.

Also as heater element 15 is heated it naturally tends to expand and my preferred construction 65 as shown, prevents cracking of or damage to insulator 14 by providing the small clearance space shown between elements 15 and 14, permitting element 15 to move with respect to element 14 as element 15 is heated.

Further it will be observed that electrically conductive surface 22 on insulator 14 extends substantially over a greater portion of insulator 14 than heater element 15 extends into. Thereby the electrostatic field of force set up by application 75 of electricity to member 15 is substantially shielded by conductive coating 22. To further afford this desired result, as shown, it will be observed that the electron emitting surface 8, preferably 80 does not cover the entire surface of conductive coating 22, so that electrons may be emitted from surface 22 substantially free from undesired interfering electrostatic forces set up by normal flow of electricity through heater wire 15.

It is an important advance in this art to have 85 the cathode conductive surface 14 cover more area of insulator 14 than is employed to support electron emitting surface 8 via said conductive surface 22. Also it is an advance in this art to have heater wire 15 and electron emitter surface 90 8 so relatively disposed with respect to electrically conductive coating 22 that surface 22 not only extends between elements 15 and 8 but also projects beyond the relatively adjacently disposed members 15 and 8. Also it is an important advance in this art to have member 15 95 relatively loosely mounted with respect to insulator 14 so as to have substantially a free closely spaced relation with respect thereto.

It will also be evident that members 15, 14, 22 100 and 8 are preferably so relatively mounted with respect to grid 12 and plate 13, as shown, that the electron stream set up by emitting surface 8 strikes members 12 and 13 substantially free from the influence of fields of force normally set up by the flow of electricity through heater wire 15. Thereby means are afforded to prevent grid 12 from being electrically detrimentally influenced by fields of force extending from heater element 15.

It will be evident that tube member 6 affords an insulating member or envelope between heater 10 and metal coating 7 of electron-emitter 8. Having now set forth an exemplification of my invention, it will be obvious to anyone skilled in this art that same may be used in any customary manner known in said art, and that various changes may be made without departing from the spirit of my invention and within the scope 10 of the appended claims.

I claim:

1. In a radio vacuum tube, a glass bulb having a hollow re-entrant cathode holder projecting inwardly therein, and closed at its end to form 15 with the bulb a continuous envelope, a cathode supported on said holder, a heater element renewably held within said holder adjacent to said cathode, and cooperating grid and plate electrodes sealed in said bulb, said bulb being evacuated and said vacuum maintained by the continuous 20 surface of said glass bulb.

2. In a three element vacuum tube having a sealing bulb, the improvement which comprises a divided structure for the cathode element thereof, 25 consisting of an electron emitting part and a thermal element for actuating said electron emitting part, and an insulating tube formed as a part of said sealing bulb and extending between 30 said electron emitting part and said thermal element, and a connector support for said thermal element to hold the same in operative position with respect to said sealing bulb and said insulating tube.

3. In an audion having an envelope, a cathode, 35 and grid and plate electrodes therefor, a structure for said cathode comprising a hollow insulating member, a heater element disposed in and spaced from said insulating member, an electrical conductive coating externally carried by 40 said insulating member, and a surface coating on said conductive member capable of emitting electrons when said conductive member is heated.

4. In an audion having an envelope, a cathode, 45 and co-operating electrodes therefor, a structure for said cathode comprising a hollow insulating member, a U-shaped heater element disposed in and spaced from said insulating member, an electrical conductive coating externally carried by 50 said insulating member, and a surface coating on said conductive member capable of emitting electrons when said conductive member is heated.

5. In a vacuum tube having an envelope, a cathode, and co-operating electrodes therefor, 55 said cathode comprising an insulator member, an electrical conductor coated on said insulator member, a coating capable of emitting electrons contacting with said electrical conductor, and an electrical heater element disposed to heat said insulator member, said electrical conductor not only extending between but also projecting beyond 60 said heater element and said coating.

6. In a vacuum tube having an envelope, a cathode, and co-operating electrodes therefor, 65 said cathode comprising an insulator member, an electrical conductor coated on said insulator member, an oxide coating capable of emitting electrons covering a substantial portion but not all of said electrical conductor, and an electrical heater element disposed within said insulator member to heat same, the portion of said electrical conductor not so coated by said electron emitting coating projecting beyond the heater 70 element.

7. In an audion having an envelope, a cathode,

and co-operating electrodes therefor, a structure for said cathode comprising a hollow insulating member, a heater element disposed in and spaced from said insulating member, an electrical conductive coating externally carried by said insulating member, and a surface coating on said conductive member capable of emitting electrons when said conductive member is heated. 80

8. In a thermionic device, an evacuated container having a re-entrant portion of insulating material, a cathode within the container and in engagement with the re-entrant part of the wall thereof, a heating device external to said container and within the recess formed by said re-entrant portion and means for retarding flow of 90 heat from said recess to the external air. 85

9. An equipotential vacuum tube having a vitreous envelope which is coated on its inner surface with an electron-emitting material to constitute a cathode, and means outside of the 95 envelope for rendering the material thermionically active.

10. A cathode structure comprising a single hollow member adapted to emit electrons when heated, a heating member within said emitter 100 and a plug engaging an end of said emitter and having an enlarged portion extending outwardly beyond the end thereof, for maintaining said heating member in spaced relation to said emitting member. 105

11. In a vacuum tube having an envelope, a cathode, and co-operating electrodes therefor, said cathode comprising an insulator member, an electrical conductor carried on said insulator member, a coating capable of emitting electrons 110 contacting with said electrical conductor, and an electrical heater element disposed to heat said insulator member, said electrical conductor not only extending between but also projecting beyond said heater element and said coating. 115

12. In a vacuum tube having an envelope, a cathode, and co-operating electrodes therefor, said cathode comprising an insulator member, an electrical conductor carried on said insulator member, an oxide coating capable of emitting 120 electrons covering a substantial portion but not all of said electrical conductor, and an electrical heater element disposed within said insulator member to heat same, the portion of said electrical conductor not so coated by said electron emitting coating projecting beyond the said adjacently disposed heater element. 125

13. In a thermionic device, a cylindrical cathode, a heating device therefor, and an evacuated envelope electrically separating the heating device from the cathode, the heating device being external to said envelope and heating the cathode by heat radiation through the envelope from the heating device, whereby the heating device is readily replaceable. 130

14. In a thermionic device, a cylindrical cathode, a heater element therefor, and an evacuated envelope electrically separating the heater element from the cathode, the heater element being external to said envelope and heating the cathode by heat radiation through the envelope from the heater element, said heater element being adapted to be heated by the passage of an electric current therethrough, whereby the heater element is readily replaceable. 135

15. In a thermionic vacuum tube, a cathode structure comprising a electrode, an electron emitting element thereon, an insulator supporting said electrode, and a heater filament disposed in said insulator, said electrode extending 140 145

- as a shield between said filament and said electron emitting element and projecting beyond the electron emitting element.
16. In a vacuum tube having a cathode, a structure for said cathode which comprises a hollow electrical insulator capable of transferring heat, a U-shaped heater filament expansibly disposed therein so that said filament may freely expand when heated with respect to said insulator, an electrode carried by said insulator and insulated thereby from said filament, and an electron emitting coating on said electrode. 80
17. In a thermionic tube having a cathode, a structure for said cathode which comprises an electrical insulator capable of transferring heat, a U-shaped heater filament expansibly disposed therein so that said filament may freely expand when heated with respect to said insulator, an electrode disposed about said insulator and insulated thereby from said filament, and an electron emitting coating on said electrode, the electrode projecting beyond the electron emitting coating so as to form a shield therefor. 85
